GEORGE STEPHEN PROCTOR AND JOHN BARRETT PRENDERGAST, OF OTTAWA,
ONTARIO, CANADA.

FILM-WINDING DEVICE.

1,113,247.

Specification of Letters Patent.

Patented Oct. 13, 1914.

Application filed June 3, 1913. Serial No. 771,463.

To all whom it may concern:

Be it known that we, GEORGE STEPHEN PROCTOR and JOHN BARRETT PRENDERGAST, both residing at the city of Ottawa, Province of Ontario, Dominion of Canada, having invented certain new and useful Improvements in Film-Winding Devices, do hereby declare the following to be a full, clear, and exact description of the same, such as will enable others skilled in the art to which it appertains to make and use the same.

The invention relates to film winding devices, for use with moving picture films, and the objects of the invention are to provide an apparatus which will wind the film after it has passed through the lantern on to a spool in such a manner that there is no necessity to re-wind the film before it is ready for use a second time, thus not only saving the time and labor occupied in re-winding, but reducing the wear and tear of the film very materially.

The invention consists essentially in the novel construction and arrangement of parts more particularly set forth in the accompanying specification and the drawings that form part of the same.

In the drawings: Figure 1 is a perspective view of a portion of the apparatus with the sliding arm in its "out" position. Fig. 2 shows an elevation partly in section of the device with the "sliding arm" in its "in" position. Fig. 3 shows a perspective view of a suitable spool for use with the device. Fig. 4 shows a perspective view of a suitable form of adjusting gear adapted to operate the adjusting rollers which guide the film when it is being wound spirally inward on its spool. Fig. 5 shows a diagram, indicating the method in which the device operates, and the path taken by the film during re-winding.

Referring to the drawings: 1 is the frame which may be of cast iron, and has provision such as the bolt-holes 2 for securing to the floor or re-winding bench; and also has a vertical arm 3 provided at its upper extremity with a horizontal orifice 4 and means 5 for securing a horizontal spindle 6 in the orifice.

7 is a pulley rotatably mounted on the spindle 6, and having provision, which may take the form of a pin 8 adapted to fit the groove 9, or other suitable means of preventing lateral movement of the pulley 7 on the spindle 6.

10 is the winding drum, consisting of a disk or arms 11 with a cylindrical flange 12; and in the flange 12 commencing from the extreme outer edge 13, is a single narrow slit 14 parallel to the axis of the winding drum, 60 and cut nearly the whole way across the flange 12. This slit is adapted to allow the end 15 of the film being re-wound to pass through it, but narrow enough not to allow the clip 16 which is then fastened to the end 65 15 of the film, to pass it; thus the end of the film is secured at the outside of the drum, preparatory to re-winding which commences with the first coil being wound in the inner periphery of the winding drum 11, and the 70 subsequent coils on the inside of the first coil; thus the film is re-wound spirally inward, commencing from the outside.

17 is a plate provided with a plurality of lugs or a flange 18 on its outer periphery, 75 and is centrally and non-rotatably secured to the spindle 6; preferably in a manner that it may be removed when desired, as for instance by the removal of the screws 19.

20 is a distance piece, which is preferably 80 secured to the plate 17, and is provided with orifices or bearings 21 suitable for receiving the ends 22 of the roller adjusted screws 23, whose opposite ends 24 are journaled in the lugs or flange 18, in such a position as to 85 make the adjustment screws 23 point radially outward from the center of the device; also allowing them free rotation but no end play.

25 are nuts adapted to be operated by the 90 screws 23 radially inward or outward, and each having a pin 26 extending at right angles to the adjusting screws, on which pin is secured the roller 27. The nuts 25 may either be made solid where they engage with 95 the screws 23 or may be made split and provided with a hinge 28 and locking device 29 as shown in Fig. 4.

30 is a "star-wheel" attached to, or formed as part of the screws 23, at the end 100 22 thereof, and adapted to be actuated by the pin or projection 31 which is formed on the winding drum disk or arms 11; this pin causes the star-wheel to rotate a fraction of a revolution for each complete revolution of 105 the winding drum; the amount of the fraction of a revolution being governed by the number of teeth in the said star-wheel.

32 is the film spool composed of the two 110 side plates 33 and 34, each of which is pref-

erably a sheet metal lamination comprising an outer ring 35, as many arms 36 as there are adjustment screws 23 used in the particular device for which it is adapted to be used, each of such arms 36 having a radial slot 37 adapted to provide a clearance for the roller 27; and if found desirable, the edge 38 of the said slot 37 may be bent outward, in order to strengthen the side plates; 10 also the inner 39 and outer circumference 40 may be flanged for the same purpose.

The side plates are held together by a drum 41 arranged with its axis concentric with the axis of the device and having a 15 slot cut away completely to allow the film entry to the spool from the inside thereof; at each side of the slot are the rollers mounted on pins 42.

The side plate 34 is provided with any 20 suitable means of attachment, such as the split expanding pins 43, to the plate 17; so that the spool is to all intents and purposes when mounted on the device, a non-rotatable fixture, in between the walls or side plates 25 of which the film is to be re-wound.

44 is a spindle secured at one of its ends into the lateral projection 45 of the frame 1, and provided at its opposite end with a head or collar 46, or other suitable means for preventing the removal of the sliding arm 47.

A keyway 48 is cut in this spindle 44, adapted to receive the key 49 secured to the sliding arm 47, and this keyway may extend from the head 46 of the spindle to where the 35 spindle is secured to the lateral arm 45.

50 is a spring fitted to a recess at the bottom of keyway 48, and is secured thereto at one of its ends by the screw or rivet 51, while the other end 52 is adapted when in its 40 normal position to rest against the end of the key 49, at such time as the sliding arm 47 is adjacent to the arm 45 of the frame; thus locking the sliding arm in this position.

By depressing the end 52 of the spring 45 into the recess in the spindle formed to receive it, the arm 47 may be pulled out till it assumes the position indicated by dotted lines in the drawing, or until it is touching the head 46 of the spindle; and this distance 50 is sufficient to allow of the film spool 32 being withdrawn in a lateral direction from the winding drum 11, and then lifted out without touching either the winding drum or the spindle 53 which is attached to the 55 sliding arm 47.

The spindle 53 may be welded into the sliding arm, or may be adjustably secured therein as shown in the drawing, and is provided at its end remote from the arm with 60 a projection 54 adapted to center the spindle, and to keep it central, with the rest of the device, when the said projection enters itself in the center of the plate 17.

55 is a loose pulley rotatably secured to 65 the said spindle 53, and provided with means

such as the pin 56 acting in the groove 57 formed in the spindle, adapted to prevent end play of the pulley on the spindle. This pulley may be formed of wood if found suitable, and is preferably provided on its periphery with a slightly raised thread 58, of a pitch a trifle greater than the width of the film which is to be re-wound in the device. The purpose of this thread is that it may assist in introducing the end of the film into the device at the commencement of the re-winding.

59 is a jockey pulley set at such an angle relative to the axis of the device as to prepare the film for the helical single twist it makes around the pulley 55, and it is rotatably mounted on a spindle 60, and also has on its side remote from the axis of the device, the roller 61 mounted on the pin 62, which is designed to prevent excessive twisting or buckling of the film, also is adapted to prevent the film coming off the pulley.

In the operation of the device (Fig. 5) the end of the film is introduced into the device by passing it between the rollers 59 and 61 and then giving it approximately one and a half turns around the loose roller 55. The raised thread 58 on the roller 55 will give one the correct "pitch" or amount of side-travel that the film is to have on the roller. The end of the film is then directly under the opening in the central drum of the spool and is brought up through this opening, over the rollers 42 and 27 and up through the slot 14 on the winding drum on the outer side of which slot the clip 15 is fastened to it, and by the revolving of the pulley 7, and with it the winding drum 10, the film is gradually wound inward on itself between the sides of the spool.

It is well known that usually the practice obtains at the present of winding a film before the lens on to a spool, so arranged that the film is wound outward on itself and therefore before using the film again, it has to be re-wound on to another spool, and this invention will make this process considerably simpler.

The spools when full of film are mounted on any suitable form of face plate or spindle 115 free to revolve as is found necessary, and passed through the lantern out to an exactly similar spool in the device described, when they are immediately ready for use again without further work or delay.

What we claim as our invention is:

1. In a device of the class described in combination, a frame; a spindle; a pulley; a peripherally flanged drum secured to said pulley and adapted to rotate on said spindle 125 having a slit in the peripheral flange said slit being adapted to receive and have secured thereto the end of a film; guide pulleys adapted to guide the film into a spool carried by the aforesaid spindle, and guide 130

rollers adapted to assist in and automatically adjust the arrangement of the film in its inward spiral rewinding.

2. In a device of the class described, a frame, a spindle, a peripherally flanged winding drum rotatably mounted on said spindle; a lateral projection from said frame, a spindle, said last mentioned spindle being parallel to the first mentioned 10 spindle; a keyway therein, a sliding arm slidably secured on said last mentioned spindle; loose guide pulleys on said arm, said guide pulleys being adapted to give the film a helical twist; a spool carried by 15 said first mentioned spindle and adapted to closely fit the interior of said winding drum.

3. In a device of the class described, a frame, a rotatably secured winding drum provided with a pulley; a plate secured to 20 said frame; a film spool; radial adjusting screws rotatably mounted on said plate; star wheels mounted on said adjusting screws; a projection on said winding drum adapted to operate said star wheels; nuts 25 rotatably secured to said adjusting screws; laterally projecting pins secured to said nuts; rollers mounted on said pins; said rollers being adapted by reason of the relative proportions of said star wheels and 30 said adjusting screws to move radially toward the axis of said drum in synchronism with the inwardly accumulating coils of the film whose position said rollers are adapted to adjust.

35 4. In a device of the class described, a frame, a winding drum rotatably secured thereto, a plate secured to said frame, said plate having radially adjustable rollers attached thereto, a spool adapted to be secured to said plate, said spool comprising two side disks having radial slots adapted to receive said radially adjustable rollers, and said disks being secured one to another by a drum having a slit and at the edges of 45 the slit having pins fitted with rollers, said pins and rollers being arranged close to the inner periphery of said disks.

5. In a film winding apparatus, a frame, a winding drum mounted thereon; a spool 50 secured to said frame, a sliding arm slidably secured to a projection on said frame; jockey pulleys rotatably secured to said sliding arm; a spring secured to said projection and adapted to lock said arm in its 55 position nearest said winding drum.

6. In a film winding apparatus, a frame, a winding drum mounted thereon; a roller-adjusting plate secured to said frame; a

film spool, a sliding arm slidably secured to a lateral projection from said frame; 60 jockey pulleys rotatably secured to said sliding arm; a projection on the spindle of one of said jockey pulleys adapted to fit into an orifice in said roller-adjusting plate, and to steady the sliding arm thereby. 65

7. In a film winding apparatus, a frame, a winding drum rotatably mounted thereon; a spool adapted to be secured to said frame and be wound with film by the rotation of said winding drum; a jockey pulley secured to said frame and rotating on the same axis as the winding drum; a guide jockey wheel having an inclined axis relative to the previously mentioned jockey pulley; said wheel being adapted to guide the 70 film on to the jockey pulley in a manner adapted to give the film a helical twist. 75

8. In a film winding apparatus, a frame, a winding drum rotatably mounted thereon, a plate having adjusting screws adapted to 80 be operated by said winding drum mounted thereon; a film spool, nuts adapted to carry guide-rollers, said nuts being adapted to be operated by said adjustment screws, and being split in a direction parallel to the axis 85 of the screws which operate them, the two halves of said nuts being hinged at one side, and adapted to be locked together in their closed position on said adjusting screws by a locking device on their sides remote from 90 said hinge.

9. A film winding apparatus comprising a frame having a vertical arm and a sliding arm, a spindle carried by said vertical arm, a winding drum mounted on said 95 spindle, a film spool disposed about said spindle and within said winding drum, and a jockey pulley carried by said sliding arm adapted to contact with and guide the film.

10. A film winding apparatus comprising 100 a frame having a vertical arm and a sliding arm, a spindle carried by said vertical arm, a winding drum mounted on said spindle, a film spool carried by said spindle and adapted for horizontal movement, and angularly disposed means carried by said sliding arm adapted to contact with and guide the 105 film.

In witness whereof we have hereunto set our hands in the presence of two witnesses. 110
